UNITED STATES PATENT OFFICE

157,041

SPOON OR SIMILAR ARTICLE

William H. Gerth, Oneida, N. Y., assignor to Oneida Ltd., Oneida, N. Y., a corporation of
New York

Application February 25, 1949, Serial No. 1,078

Term of patent 14 years

(Cl. D54—12)

To all whom it may concern:

Be it known that I, William H. Gerth, a citizen of the United States, residing at Oneida, county of Madison, and State of New York, have invented a new, original, and ornamental Design for a Spoon or Similar Article, of which the following is a specification, reference being had to the accompanying drawing, forming a part thereof, in which:

Figures 3, 4 and 5 are sections taken on the respective lines 3—3; 4—4 and 5—5 of Figure 1.

The essential features of my design for a spoon or similar article reside in the configuration of the handle in combination with the particular type of ornamentation as applied thereto.

I claim:

The ornamental design for a spoon or similar article, substantially as shown and described.

WILLIAM H. GERTH.
